**TWO WAY PLOW CONSTRUCTION WITH MEANS
TO LIMIT ROTATION OF CARRIER**
Harry A. Pursche, 16813 S. Vermont Ave.,
Gardena, Calif.
Filed Feb. 9, 1956, Ser. No. 564,462
6 Claims. (Cl. 172—224)

This invention relates to agricultural implements and is particularly directed to improvements in two way plows. This invention relates to improvements over the devices shown in my prior Patents 2,625,089, 2,625,090, 2,625,091 and 2,666,376.

It is an object of this invention to provide an improved form of two way plow having a novel type of resilient action which cushions shock occasioned by plowshares striking an obstruction, as well as providing frangible means which protects the major components of the structure from damage.

Another object is to provide a two way plow construction having a carrier which turns about a longitudinal axis and which is provided with a novel form of latch for securing the carrier in either of two operative positions.

Another object is to provide a two way plow in which novel means are provided for turning the carrier on its longitudinal axis.

Another object is to provide a two way plow having a novel form of depth control device which includes a pair of tail wheels each adapted to roll on unplowed ground.

Another object is to provide a tractor-mounted two way plow having novel means for supporting a portion of the weight of the plow assembly in operative position on the tractor in order to provide desired traction.

Other, related, and more detailed objects and advantages will appear hereinafter.

In the drawings:

FIGURE 1 shows a preferred embodiment of my invention and illustrating a two way plow mounted on the draft links of a tractor.

FIGURE 2 is a view similar to FIGURE 1, showing the plow assembly in operative position.

FIGURE 3 is a side elevation partly broken away.

FIGURE 4 is a sectional end elevation taken substantially on the lines 4—4 as shown in FIGURE 3.

FIGURE 5 is a view showing a portion of FIGURE 3 and showing the tail wheel arms connected for dependent movement.

FIGURE 6 is a plan view partly in section and partly broken away, the plowshares being omitted for clarity of illustration.

FIGURE 7 is a sectional elevation taken substantially on the line 7—7 as shown in FIGURE 3.

FIGURE 8 is a fragmentary plan view similar to FIGURE 6 but showing the parts in a different position.

FIGURE 9 is a sectional plan view taken substantially on the lines 9—9 as shown in FIGURE 3.

FIGURE 10 is a sectional end elevation taken substantially on the lines 10—10 as shown in FIGURE 3.

FIGURE 11 is a side elevation partly broken away, showing a modified form of my invention.

FIGURE 12 is a plan view partly in section, showing the device of FIGURE 11.

FIGURE 13 is a side elevation similar to FIGURE 11 but showing the parts in different position.

Referring to the drawings, the tractor generally designated 10 is provided with draft links 11 which extend rearwardly from the tractor and which may be raised and lowered through hydraulically-actuated arms 12 mounted on the tractor. The draft links 11 provide sockets for the detachable connection of various implements, and latch

2

means (not shown) are provided for securing the implements to the links 11.

In accordance with my invention, I provide a frame 15 which includes a longitudinal beam 16 fixed to the cross beam 17. The frame 15 is supported by means at the outer ends of the cross beam 17 and, as shown in the drawings, this means includes the subframe 18 having parallel arms 19 and 20 connected by the cross bar 21. Pivot bolts 22 and 23 connect the subframe 18 to the frame 15. An upstanding post 24 is fixed on the frame 15 and is connected by a link member 25 of adjustable length to the cross bar 21. Turning of the turnbuckle 26 which comprises a portion of the link 25 serves to vary the angular position of the frame 15 relative to the subframe 18. Forwardly extending terminal pieces 27 are provided on the arms 19 and 20 and these are releasably connected to the hydraulically operated draft links 11 on the tractor 10.

A carrier 28 includes a tubular element 29 mounted to turn on the outer surface of the longitudinal beam 16. This carrier 28 supports one or more right hand plows 30 and one or more left hand plows 31. Each pair of right hand plows and left hand plows is mounted on opposite ends of a plow beam 32, 33, releasably attached to the carrier 28 by means of J bolts 34. The construction is such that the beams 32 and 33 may be mounted in the full line position shown in FIGURE 9 or in the phantom line position shown in the same figure, and this way plowshares of different effective widths may be mounted on the same carrier 28.

A collar 36 is fixed on the longitudinal beam 16 near the rearward end thereof and is provided with a central aperture 37. A bolt 38 is slidably received in this aperture 37 and extends axially of the beam 16. A collar 39 slides on the bolt 38 and a relatively heavy coil spring 40 is confined between the collars 36 and 39 and encircling the bolt 38. A relatively light coil spring 41 is confined between the collar 39 and the washer 42 adjacent the bolt head 43. A sleeve 44 encircling the bolt 38 within the light spring 41 serves to limit the extent of compression of the light spring 41. The bolt 38 passes through an opening 45 in the thrust plate 46 which passes over the rearward end of the tubular member 29 on the carrier 28. The washer 47 and nut 48 serve to transmit forces from the bolt to the carrier 28. From this description it will be understood that draft force applied to the longitudinal beam 16 passes through the collar 36, springs 40 and 41 to the bolt 38 and thence to the carrier 28 through nut 48 and washer 47. The bolt 38, therefore, comprises a frangible tension element serving as a connection between the frame 15 and the carrier 28.

Means are provided for turning the carrier 28 on the longitudinal axis of the beam 16. As best shown in FIGURES 3, 6, and 7, this means comprises a sprocket 49 mounted on a hub 50 which is free to turn on the beam 16. This sprocket is connected by a chain 51 to the driving plate 52. The plate 52 is provided with a supporting trunnion 53 received in a bearing 54 mounted on the cross beam 17. The plate has a curved outer periphery 55 and the chain 51 extends around this outer periphery. The ends of the chain are anchored to the plate, as shown at 56 and 57.

A double-acting power cylinder assembly generally indicated 58 is pivotally connected at 59 to a bracket 60 mounted on the cross beam 17. The piston rod 61 extending from this assembly 58 carries a clevis 62 at its extending end, and this clevis is pivotally connected to the pin 63 fixed on the plate 62. Connections 64 and 65 for pressure fluid are mounted at opposite ends of the power cylinder assembly 58 so that the piston rod 61 can be moved under power in either direction. Pressure fluid

for operating the assembly 58 may conveniently be derived from the hydraulic system of the tractor.

A socket 66 is fixed on the outer surface of the hub 50, and a drive pin 67 is fixed in the socket. The pin 67 is slidably received within an opening 68 provided in the plate 69 fixed on the carrier 28.

From this description it will be understood that the carrier 28 may be turned about the longitudinal axis of the beam 16 by actuation of the power cylinder assembly 58. When the piston rod 61 is extended, the driven sprocket 49 is caused to turn in a counter-clockwise direction as viewed in FIGURE 7, and when the piston rod 61 is retracted, the sprocket 49 is turned in a clockwise direction. Engagement of the drive pin 67 with the torque receiving element 69 on the carrier 28 serves to turn the carrier and right and left hand plows 30 and 31.

Stop means are provided for limiting the angular movement of the carrier 28 with respect to the beam 16. As best shown in FIGURES 9 and 10 of the drawings, this stop means includes a pair of duplicate arms 70 and 71 which are pivotally mounted on the carrier 28 at 72 and 73, respectively. These arms extends outwardly from the axis of the beam 16 and each is provided with a roller 74, 75 at its outer end. A clamp plate 76 is provided with axially extending pins 77 and 78 and a central adjustable bolt 79 which extends through a radial slot 80 in the plate 69. It will be understood that adjustment of the clamp plate 76 in a radial direction with respect to the beam 16 serves to spread the rollers 74 and 75 or to draw them closer together, since the pins 78 and 77 engage the outer surfaces of the arms, and the bushing 81 engages the inner surfaces thereof.

The roller 75 on the arm 71 is adapted to contact the upper surface 82 of the rearwardly-extending abutment plate 83 which is fixed on the frame 15. Similarly, the roller 74 on the arm 70 is adapted to engage the upper surface 84 on the rearwardly-extending abutment plate 85, also fixed on the frame 15. Each of the abutment plates 83 and 85 carries a member 86, 87 at its rearwardly-extending end, which member provides a downwardly facing lip 88, 89. When the relatively light spring 41 compresses by reason of the draft force of the plowshares in the ground, the carrier 28 moves rearwardly with respect to the longitudinal beam 16, with the result that one of the rollers passes beneath its respective lip. Thus in the position shown in full lines in FIGURE 10, the roller 75 on the frame 71 passes under the lip 88. In the phantom line position shown in FIGURE 10, the roller 74 on the arm 70 passes under the lip 89. The draft force on the plowshares thus acts to latch the carrier 28 against turning movement and thereby maintain the plowshares in proper operating position.

A novel form of tail wheel assembly is provided for regulating the depth of cut, as best shown in FIGURES 3-6. A bracket 90 at the rearward end of the carrier carries a pair of pivot bolts 91 and 92. An arm 93 is mounted on the pivot bolt 91, and a duplicate arm 94 is mounted on the pivot bolt 92. A tail wheel 95 is mounted to turn on the outer swinging end of the arm 93, and a similar tail wheel 96 is mounted to turn on the outer swinging end of the arm 94. The location of the wheels is offset from the axis of the beam 16 so that each of the wheels rolls on unplowed ground.

When it is desired to plow to relatively shallow depths, links 97 and 98 are employed for fixing the arms 93 and 94 against swinging movement. As shown in FIGURE 3, the links may be connected by means of a common bolt 99 to any one of a plurality of apertures 100 provided in the plate 101 fixed on the carrier 28. The outer ends of the links may be fixed by means of bolts 102 to any one of the apertures 103 provided on the arms 93 and 94. The tail wheel 96 serves to control the depth of cut of the left hand plows 31, and the tail wheel 95 similarly serves to control the depth of cut of the right hand plows 30.

For relatively deep plowing, only one of the links 97 (or 98) is employed. The apertures 100 are not used. The link 97 is then pivotally connected at one end to the pivot pin 104 fixed on the arm 93, and is pivotally connected at the other end to the pivot pin 105 fixed on the arm 94. The arms 93 and 94 then swing substantially as a unit about their respective pivot bolts 91 and 92. Stop lugs 106 and 107 are fixed in apertures 100 and serve to limit the swinging movement of the wheels 95 and 96. Thus the stop lug 106 engages the arm 93 to limit pivotal movement of the tail wheel assembly in one direction, and the stop lug 107 engages the arm 94 to limit pivotal movement of the assembly in the other direction.

Means are provided for transferring a portion of the weight of the plow assembly to the rear wheels of the tractor 10 in order to improve traction. As shown in the drawings, this means comprises a spring housing 110 fixed on the tractor frame by any convenient means such as, for example, the detachable arm 111. A coil spring 112 within the housing rests on an annular abutment 113 at one end, and engages a collar 114 at the other end. A nut member 115 is threadedly received on the upper end of the rod 116 so that turning of the nut 115 serves to vary the extent of compression of the spring 112. A tension chain 117 is connected to the lower end of the rod 116 and is also connected to the element 118 on the subframe 18. The nut 115 is adjusted so that when the plowshares are operating at the desired depth, a downward force of the desired magnitude is applied to the spring 112. This force results from tension in the chain 117 and transmits a downward force to the frame of the tractor. The magnitude of this downward force is determined by the setting of the nut 115. Minor variations in the level of the ground surface do not result in material variations in the tractive effort, and hence slipping of one rear driving wheel of the tractor does not permit it to dig a hole and escape the effect of the weight of the plow assembly. Traction is thereby improved materially.

The light spring 41 compresses under drag of the plows in the earth and thereby permits the rollers on the ends of the bars 70 and 71 to enter latching position under the lips 88 or 89. The heavy spring 40 does not compress materially, however, unless the plows should strike an obstruction. If a very severe shock is encountered of a magnitude which would cause permanent damage to the plow assembly, the tension bolt 38 fails permitting the carrier 28 and plows 30 and 31 to remain stationary while the tractor 10, frame 15 and longitudinal beam 16 continue forward movement.

Means are provided to prevent axial movement of the driven sprocket 49, and as shown in FIGURES 7 and 9 of the drawings. This means comprises a stop lug 120 which normally has clearance with one side of the sprocket 49 but which prevents axial movement of the sprocket in a direction away from the cross beam 17. This stop lug 120 is fixed to an annular spacer 121 which is clamped to the rear face of the cross beam 17 by means of the bolt 122. A pin 123 fixed on the spacer 121 extends into a small opening provided on the cross beam 17 to prevent rotation of the spacer 121 and stop lug 120. As shown in FIGURE 7, the position of the bolt 122 and stop lug 120 lies between the flights of the chain 51, and between the cam 52 and the sprocket 49.

In the modified form of my invention shown in FIGURES 11-13, a different type of latching mechanism is provided for preventing the carrier 28a from turning relative to the longitudinal beam 16a. In this form of my invention, the carrier 28a does not move longitudinally with respect to the beam 16a, and the sprocket 49a is fixed directly to the forward end of the carrier. In other respects the carrier 28a and the right and left hand plows and plow beams are substantially the same as that previously described. The tail wheel assembly

may be similar to that described above. In accordance with this form of my invention, an arm 130 extends forwardly at an angle from a bracket 131 fixed on the carrier 28a. The forward end of this arm 130 carries a cross arm 132. This cross arm is internally threaded to receive the threaded shanks 133 of the latch elements 134 and 135. The elements 134 and 135 may be adjusted by means of these threads to vary the extent of projection from the cross arm 132.

The element 134 is adapted to engage the upper surface of the stationary abutment plate 136 fixed on the frame 15a. Similarly, the element 135 is adapted to engage the upper surface of the abutment plate 137 also fixed on the frame 15a.

Latch bars 138 and 139 are slidably mounted on the frame 15 adjacent the abutments 136 and 137. Spring 140 acts to move the latch bars rearwardly to engage their respective stop elements 134 and 135, respectively. Bell cranks 141 and 142 are pivoted to the frame 15a and to the latch bars 138 and 139, respectively. Each bell crank adjustably supports a laterally extending pin 143 which underlies a portion of the draft links 11a. When the draft links 11a are raised, as shown in FIGURE 13, the resulting angularity between the draft links and the frame 15a causes the bell cranks 141 and 142 to retract the latch bars 138 and 139 against the action of the springs 140. The carrier 28a may then be turned on the beam 16a. The forward end of each latch bar is chamfered or slanted as shown at 144 to enable its respective stop element to move the latch bar against the action of the spring 140 when moving toward latching position.

Having fully described my invention, it is to be understood that I do not wish to be limited to the details herein set forth, but my invention is of the full scope of the appended claims.

I claim:

1. In a two way plow, the combination of: a frame including a stationary longitudinal beam, a carrier mounted to turn on the beam and having a right hand plow and a left hand plow mounted thereon, a pair of laterally spaced abutments on the frame, a pair of stop elements adjustably mounted on the carrier and each adapted to engage one of said abutments to limit turning movement of the carrier in either direction, each stop element comprising an arm pivotally mounted on the carrier and extending outward from the axis of the beam, and single means on the carrier for securing both of the arms in adjusted position.

2. In a two way plow, the combination of: a frame including a stationary longitudinal beam, a carrier mounted to turn on the beam and having a right hand plow and a left hand plow mounted thereon, a pair of laterally spaced rearwardly projecting abutments on the frame, a pair of stop elements mounted on the carrier and each adapted to engage one of said abutments to limit turning movement of the carrier in either direction, each stop element comprising an arm pivotally mounted on the carrier and extending outward from the axis of the beam, and radially movable means on the carrier engaging each of the arms for simultaneously swinging them in opposite directions.

3. In a two way plow, the combination of: a frame including a stationary longitudinal beam, a carrier mounted to turn on the beam and having a right hand plow and a left hand plow mounted thereon, a pair of laterally spaced rearwardly projecting abutments on the frame, a pair of arms pivotally mounted on the carrier and extending outward from the axis of the beam and each adapted to engage one of said abutments to limit turning movement of the carrier in either direction, a radially movable element on the carrier engaging each

of said arms for simultaneously changing their angular positions on the carrier, and means for securing said element in adjusted position on the carrier.

4. In a two way plow, the combination of: a frame including a stationary longitudinal beam, a carrier mounted to turn on the beam and having a right hand plow and a left hand plow mounted thereon, a tail wheel assembly mounted on the carrier at the rearward end thereof, said assembly including a pair of arms each pivotally mounted on the carrier at one side of the axis of said beam, a wheel mounted on the swinging end of each arm and adapted to roll upon unplowed ground, and means for selectively fixing the arms in adjusted position relative to the frame said means including a multiple perforated attachment element incorporated in each arm, a perforated plate secured to each carrier, and link and bolt means adapted to utilize said perforated plate and attachment elements thereby to secure said arms in various adjusted positions.
5. In a two way plow, the combination of: a frame including a stationary longitudinal beam, a carrier mounted to turn on the beam and having a right hand plow and a left hand plow mounted thereon, a tail wheel assembly mounted on the carrier at the rearward end thereof, said assembly including a pair of arms each pivotally mounted on the carrier at one side of the axis of said beam, a wheel mounted on the swinging end of each arm and adapted to roll upon unplowed ground, and means for adjusting the position of said arms including a multiple perforated attachment element incorporated in each arm, a perforated plate secured to said carrier, link and bolt means adapted to utilize said perforated plate and perforated attachment elements to secure said arms in various adjusted positions, at least one of said links being shiftable to span said arms and connectible therewith to permit dependent movement of said arms, and stop means mounted on said plate to limit movement of said arms when spanned by said link.

6. In a two-way plow assembly, the combination of: a frame, a carrier mounted on the frame to turn about a longitudinal axis extending in the direction of travel of the plow, a right hand plow and a left hand plow mounted on the carrier, a pair of laterally spaced stationary abutments on the frame, a pair of diverging arms each pivotally mounted on the carrier and extending outward from said longitudinal axis, the outer end of each arm being adapted to engage one of said abutments, respectively, and means including an element mounted for radial movement on the carrier for securing said arms in adjusted position on the carrier whereby the extent of turning movement of the carrier is limited in both directions.
